(57) **CLAIM**

The ornamental design for a curved lamp pole for an outdoor lighting fixture, as shown and described.

DESCRIPTION

FIG. 1 is a perspective view of a curved lamp pole for an outdoor lighting fixture.

FIG. 2 is a front elevation view of the curved lamp pole for an outdoor lighting fixture of FIG. 1, a back elevation view being a mirror image.

FIG. 3 is a left side elevation view of the curved lamp pole for an outdoor lighting fixture of FIG. 1.

FIG. 4 is a right side elevation view of the curved lamp pole for an outdoor lighting fixture of FIG. 1.

FIG. 5 is a top plan view of the curved lamp pole for an outdoor lighting fixture of FIG. 1.

FIG. 6 is a bottom plan view of the curved lamp pole for an outdoor lighting fixture of FIG. 1; and,

FIG. 7 is a perspective view of a curved lamp pole for an outdoor lighting fixture of FIG. 1 shown with an intended fixture and mounting assembly.

The broken lines are provided for illustrative purposes only and form no part of the claimed design.
